US00D504126S

(12) **United States Design Patent** (10) Patent No.: **US D504,126 S**
(45) Date of Patent: **** Apr. 19, 2005**

(54) **MICROPHONE**

(75) Inventors: **Martins Saulespurens**, Westlake Village, CA (US); **Bernard Wise**, Westlake Village, CA (US)

(73) Assignee: **Baltic Latvian Universal Electronics, LLC**, Westlake Village, CA (US)

(**) Term: **14 Years**

(21) Appl. No.: **29/204,593**

(22) Filed: **Apr. 30, 2004**

(51) LOC (7) Cl. **14-01**

(52) U.S. Cl. **D14/228**

(58) Field of Search D14/225, 226, D14/227, 228, 229; 181/158, 242; 381/157, 158, 181, 355, 356, 357, 358, 359, 360, 369, 115
